UNITED STATES PATENT OFFICE.

EDWIN RUTHVEN WHITNEY, OF MANCHESTER, NEW HAMPSHIRE, ASSIGNOR
TO THE STANDARD ELECTRIC COMPANY OF VERMONT, OF ST. JOHNS-
BURY, VERMONT.

COIN-BUCKET.

SPECIFICATION forming part of Letters Patent No. 371,868, dated October 18, 1887.

Application filed March 11, 1887. Serial No. 230,500. (No model.)

To all whom it may concern:

Be it known that I, EDWIN RUTHVEN WHITNEY, of the city of Manchester, in the county of Hillsborough and State of New Hampshire, have invented a certain new and useful Improved Coin-Bucket; and I do hereby declare that the following is a full, clear, and exact description of the same.

My invention has reference to the coin-receptacles used in connection with machines for weighing, strength-testing, and for other purposes, in which the introduction of a coin sets free either the operating or indicating mechanism; and its object is to provide a coin-bucket which shall allow only the special coin demanded for the use of the machine to operate it and to release the mechanism.

In my invention the coin-bucket is carried on a lever pivoted so that the other end of it rises when the bucket receives the coin; but in the present case the bucket is formed in two separate parts, the sides and front of the bucket being only connected to the back by being pivoted together through ears at the top. The lower parts of the front and sides and of the back of the bucket are held together by a spring, the sides themselves being so arranged as to hold the coin in the bucket until by its descent the projection on one side of it is brought into contact with any fixed point in the machine, and the resistance of the spring thereby overcome, allowing the bottom to open and the coin to fall out, the lever then resuming its normal position. Should any coin of less thickness than the one designated be dropped in, it will simply pass through the bucket without acting upon it at all.

For full comprehension of my invention reference must be had to the annexed drawings, forming part of this specification, in which—

Figure 1 is a plan view of the bucket; Fig. 2, a side view of same, partly broken away, to show the coin in position; and Fig. 3 a perspective view showing the bucket opened.

Similar letter of reference indicate like parts.

The bucket is formed, as shown, with back A, sides A' A', and front A², made in one

with each other and connected by pins passing through the ears a a and a' a'.

B is the spring by which the sides of the bucket are held against the back, and C the projection or dog, secured on front A², which, as the bucket is lowered by the weight of the coin dropped into it, comes in contact with any fixed point of the machine and opens the bottom of the bucket. D is the pivoted lever, to which the bucket is secured and through which the depression of the bucket operates to release the actuating mechanism.

D' is a knife-edge, forming a fulcrum secured at any suitable point to the under side of D, and resting in a support, D², carried from any part of the case or frame.

Any kind of a chute may be used to deliver the coin from the opening in the case of the machine to the bucket, and it is immaterial whether it is dropped into a cash-receptacle or falls into another chute.

It will be obvious that a weight attached to and resting upon the front A² will serve the same purpose as the spring B.

The introduction of too large a coin will be obviated by making the opening in the case the proper size.

Having thus described my invention, I beg to state that what I claim is as follows:

1. In a machine in which the mechanism is set free by the introduction of a coin, a bucket for the reception of such coin carried on a pivoted lever and composed of a back plate secured to such lever, sides and front made in one with each other and pivoted at top to the back, a device for holding front and back together near their lower edges, and means for opening bucket at bottom.

2. A coin-bucket composed of a back secured to pivoted lever, front and sides pivoted to said back, a spring normally holding front part and back together, and a dog secured to front part of bucket, all substantially as herein described, and for the purposes set forth.

EDWIN RUTHVEN WHITNEY.
